No. 34,162.

PATENTED JAN. 14, 1862.

C. NEER.

METALLIC BLIND FOR WINDOWS, &c.

Albany New York January 25 1861.

W. B. THOMAS

M. Warren

Arthur B. Raye.

UNITED STATES PATENT OFFICE.

CHARLES NEER, OF ALBANY, NEW YORK.

IMPROVEMENT IN METALLIC BLINDS FOR WINDOWS, &c.

Specification forming part of Letters Patent No. 34,162, dated January 14, 1862.

To all whom it may concern:

Be it known that I, CHARLES NEER, of Albany, in the State of New York, have invented, made, and applied to use a certain new and useful Improvement in Metallic Blinds; and I do hereby declare that the following is a full, clear, and exact description of the construction and operation of my said invention, reference being had to the annexed drawings, making part of this specification, wherein—

Figure 1 is a plan of part of the blind-frame. Fig. 2 is an elevation of the upper end of a blind fitted with my improvement. Fig. 3 is a vertical cross-section showing the upper and lower ends of the blind, and Fig. 4 is a sectional plan at the line *x x*.

Similar marks of reference denote the same parts.

My said invention relates, first, to a metallic strip receiving the tenons of the blind, applied to and combined with a metallic frame in a peculiar manner; second, to the construction of metallic slats applied in said frame, and, third, to the manner of fastening the slats.

In the drawings, *a a* are the vertical stiles made from flat wrought-iron bars, and connected to each other by the cross bars or rails *b b*. These stiles *a a* stand across the ends of the rails *b b* and present their edges at the sides of the blind. The rails *b b* are connected to the stiles either by passing the end of the rail through a mortise in the flat stile, as shown at 1 1, or else by bending the end of the rail at right angles, as at 2 2, to form a flange and attaching the stile by rivets. This method of forming the metallic frame for blinds enables me to use comparatively light iron, and at the same time attain great strength and stiffness in the said frame, for the wide cross bars or rails *b b* prevent the blind from sagging, and the vertical stiles render the blind stiff lengthwise of the frame.

c c are strips of thin sheet-iron bent or folded into the shape represented, and perforated with holes at the proper distance apart for receiving the tenons of the blind-slats, and these strips *c c* are kept from the stiles *a* sufficiently for introducing said tenons by means of wooden strips *3 3*, and rivets pass-

ing through the three thicknesses secure the parts together.

In order to keep the strips *c* from the stiles *a*, a T-shaped strip of metal or a corrugated strip edgewise might be introduced; but I prefer the wood *3*. The strips *c* might be placed outside the stiles *a a*, as seen in Fig. 5, and the stiles themselves be perforated for the tenons; but I prefer that said strips *c* be on the inside of the stiles, as seen in Figs. 2 and 4.

The metallic slat *d*, Fig. 3, is similar to that shown in my patent of June 15, 1858; but my improved slat *e* is shown in Figs. 2 and 3, and is formed of a metallic sheet attached at its lower edge by the cross-wire *4*, at which point it turns, and the upper ends of the slats swing open, and are connected by a vertical rod *f*, (the same as in my aforesaid patent.) In this form, however, the blinds would be apt to drop open. I therefore provide the disk or washer *5* at one or both ends of one or of several of the slats, said washer setting over the wire *4* and having a groove to take the edge of the slat, so that the two turn together, and *6* is a perforated spring setting over the aforesaid rod *4* and giving the required friction against the washer *6* to keep the said slats from falling and retain the same in any position to which they may be turned. The slats may shut against the flange 10 of the strips *c c*. The metallic blinds, formed as aforesaid, are to be mounted on hinges of any desired character, and the wooden casing usually surrounding the window-sash, and to which the said metallic blinds will be attached, is to be protected from fire by the metallic lining *g* and air-space *i*. This metallic lining is to be attached at the rabbet next the blind by nails, as at 7, and kept from contact against the face of the wood by nails *8 8*, that project from the casing, while the nails *9 9*, that pass through perforations in said metallic lining, retain the same in place. By this arrangement an air-space is left between the iron and the wood-work, effectually rendering the same fire-proof.

To prevent the metallic slats being turned, I make use of a vertical bar *h*, united by hinges *11* to the stiles *c*, and so fitted as to be

turned against or away from the slats, this device being always in place and more convenient in use than bar *h'*, inserted into staples 12 above and below the slats on the bars *b*.

Having thus described my said invention, what I claim, and desire to secure by Letters Patent, is—

1. The strips *c*, bent or folded, as shown, and applied to the iron blind-frame, composed of the vertical stiles *a a*, united to each other by the cross bars or rails *b b*, the parts receiving the tenons of the blind-slats, as set forth.

2. The metallic slats *e e*, attached at their lower corners and provided with the disk 5 and spring 6, for the purposes and as set forth.

3. The bars *h*, hinged to the blind-frame, as set forth, so that they can be turned against the slats to keep them shut, as specified.

In witness whereof I have hereunto set my signature this 28th day of January, 1861.

CHARLES NEER.

Witnesses:
